MACHINE FOR CUTTING WEBS OF MATERIAL INTO STRIPS

David N. Judelson, Park Ridge, N. J.

Application January 18, 1950, Serial No. 139,163

7 Claims. (Cl. 164—65)

1

This invention relates to a new and improved machine for cutting a web of material into strips. This material may be of any type, such as plastic, fabric, paper, etc.

One of the objects of the invention is to provide a strip cutting machine which can either cut the material into strips and also pink the edges of the strips, or merely cut the material into strips without pinking.

If the machine pinks the cut edges of the strips, the adjacent cut and pinked edges of adjacent strips may interleave or interlock. This objectionable interleaving occurs readily when the material is a thermoplastic resin or plastic, or when the material is thin.

Therefore, when the machine cuts and pinks the edges of the cut strips, alternate cut and pinked strips are fed in different directions to different take-up shafts from the cutting and pinking mechanism, in order to prevent such interleaving or interlocking.

When the machine cuts but does not pink the edges of the cut strips, they are led in the same direction from the cutting mechanism to a single take-up shaft.

I provide a main take-up shaft on which all the strips are wound when said strips are cut without pinking, and an auxiliary take-up shaft which is easily movable into and out of operating position. When the machine cuts and pinks, the auxiliary take-up shaft is maintained in operating position. When the machine cuts without pinking, said auxiliary take-up shaft is moved into non-operating position. When the machine cuts and pinks, alternate cut and pinked strips are respectively wound upon the two take-up shafts. Since adjacent cut and pinked strips are led in different directions to the respective take-up shafts from the mechanism which cuts and pinks the strips, any interleaving or interlocking of adjacent pinked edges of adjacent strips is prevented. This is particularly important when the material is a thermoplastic resin or plastic, or when the material is thin and irregular.

I thus provide a main take-up shaft on which all the strips are wound to provide rewound rolls of material rolls when said strips are cut without pinking, and an auxiliary take-up shaft to take up alternate strips when the machine cuts and pinks. It has been known to provide a machine of this general type with two take-up shafts. In such prior machines, each shaft was located in fixed position relative to the cutters and about three feet away from the cutters. Due

2

to irregularities in thickness of the material and irregularities in tension, it was impossible to form spiral rewound rolls of material of the cut strips on the take-up shafts, of even diameter. Therefore, as the operation continued, the rolls of material were under unequal tension, and the rolls of material collapsed sideways on occasions. To remedy this, it has been proposed to drive the take-up mandrels of the respective rolls of material independently by respective slip-friction drives, in order to allow for rolls of material of different diameters. According to my invention, I provide a cutting roll or drum at which the slitting is performed, and which contacts with the spirally wound rolls of strips on both take-up shafts. Each take-up shaft has a positive mechanical drive, so that both shafts are rotated in unison at the same angular velocity.

The cutting drum frictionally contacts with the rolls of material on both shafts. The angle of contact between said cutting drum and the material which passes around said cutting drum and which is fed to one of the take-up shafts, such as the main take-up shaft later described herein, is at least 180° and preferably more than 180°, so that said cutting drum is rotated with no slip relative to the strips of material which are cut on said drum.

Also, the cutting drum is forced by gravity against the rewound rolls of material on said selected shaft, which is the main take-up shaft later described herein, to provide a no-slip drive of the cutting drum relative to the material rolls on both shafts. Since the cutting drum is pressed against the rolls of material on one shaft, the rolls of material on said shaft are formed of even diameter. The rolls of material on the other take-up shaft, which is hereafter designated as the auxiliary take-up shaft, are pressed against the cutting drum without slipping, so that these rolls of material on the auxiliary take-up shaft are also formed of even diameter and under even tension.

Other objects and advantages and features of the invention are stated in the annexed description and drawings, which illustrate a preferred embodiment thereof.

Fig. 1 is a side elevation of the improved machine. In Fig. 1 the non-operating position of said auxiliary take-up shaft and certain auxiliary parts is shown in broken lines. The operating position of said auxiliary take-up shaft and its auxiliary parts is shown in full lines. When the machine cuts without pinking, the auxiliary shaft is held in non-operating position. When

3

cutting and pinking members are used in the machine, the auxiliary take-up shaft is maintained in its operating position;

Fig. 2 is a top plan view of Fig. 1;

Fig. 3 is a detail view of a part of Fig. 1, showing the aforesaid auxiliary take-up shaft and its auxiliary parts in a non-operating position which corresponds to the broken-line position of Fig. 1;

Fig. 4 is a section on the line 4-4 of Fig. 2;

Fig. 5 is a section on the line 5-5 of Fig. 1;

Fig. 6 is a section on the line 6-6 of Fig. 5;

Fig. 7 corresponds to Fig. 6. Fig. 7 shows the release position of a control collar, in order to enable the removal of the respective take-up shaft from the machine. Fig. 6 shows the locking position of said control collar in which the respective take-up shaft is releasably held in position in the machine;

Fig. 8 is a section on the line 8-8 of Fig. 1;

Fig. 9 is a diagrammatic perspective view showing the respective positions of the main take-up shaft and the auxiliary take-up shaft, when the latter is in operating position, and the machine cuts and pinks;

Fig. 10 is similar to Fig. 9, showing the auxiliary take-up shaft in its non-operating position, when the machine cuts without pinking, and all the strips are wound on the main take-up shaft;

Fig. 11 is a top plan view of one of the pinking knives and its holder; and

Fig. 12 is a top plan view of a cutting or slitting knife and its holder. This knife is used when the machine merely cuts the material into strips, without pinking the strips.

The machine has a frame F, in which a motor 1 is mounted. Said motor 1 drives a pulley 2 which actuates a belt 3 which drives a clutch pulley 4 which is associated with a companion clutch pulley 5. The pulleys 4 and 5 are free to rotate relative to their common stud shaft 6. This shaft 6 is axially shiftable. This shaft 6 may be non-rotatable relative to frame F.

As shown in Fig. 8, the shaft 6 is provided with a bearing 7 in the frame F. An end thrust washer 8 is provided between the driven pulley 5 and the bearing 7. The adjacent faces of the pulleys 5 and 4 are provided with friction strips 9 and 9a. The hubs of the pulleys 5 and 4 are hollow, and a compression spring 10 is located in said hollow hubs in order to normally space the friction strips 9 and 9a so that pulleys 4 and 5 are normally uncoupled.

A collar 11 is fixed by a pin 11a to the shaft 6 in order to limit the axial movement of the pulley 4 or shaft 6 under the force of the compression spring 10. An end-thrust washer 12 is located between the hollow hub of the driving pulley 4 and the collar 11. The bearing 7 has an integral extension 7a, whose edge is provided with clutch-operating teeth 14. A control collar 15 is turnable on the shaft 6. Said collar 15 abuts a collar 16 which is fixed to the shaft 6 by means of pin 16a. Said collar 15 is provided with teeth which intermesh with the clutch-operating teeth 14 as shown in Fig. 8. When the collar 15 is in the position shown in Fig. 8, the pulleys 4 and 5 are held uncoupled by spring 10 and they rotate freely relative to the shaft 6. When the collar 15 is turned by means of the rod 17, which is pivotally connected to an arm 18 of said collar 15, the intermeshing teeth of collar 15 and of extension 7a force the collar 15 axially to the left of its position shown in Fig. 8, thus shifting the shaft 6 axially to the left of its position shown in Fig. 8. This forces the friction strip 9a of

4

driving pulley 4 into operative contact with the friction strip 9 of driven pulley 5, thus coupling and rotating the pulleys 4 and 5 in unison relative to the shaft 6. The rod 17 consists of two sections which are adjustably connected by coupling 17b. Said rod 17 is pivoted to a pedal P.

When pulley 5 is driven, it actuates a belt 19 which rotates a pulley 20 and its shaft 20a. A gear 21 is fixed to shaft 20a of pulley 20. This gear meshes with and rotates a larger gear 22 which is fixed to the shaft 23.

As shown in Fig. 5, a double pulley 24 is fixed to the shaft 23. This double pulley 24 drives respective belts 25 and 26. The belt 25 actuates the double pulley 27. The double pulley 27 is mounted upon a shaft 27a. This shaft 27a may be a stud shaft which is fixed to frame F, in which case pulley 27 is turnable on shaft 27a. Pulley 27 may be fixed to a turnable shaft 27a.

One section or groove of the double pulley 27 actuates a belt 28, which rotates a pulley 29 which is fixed to a shaft 30.

The machine has two identical angular frames, each of which has rigid legs 31 and 32, which are optionally fixed to each other in perpendicular relation in this embodiment. The shaft 30 is mounted in said frames at the respective angular junctions between the respective pairs of legs 31 and 32. The legs 31 are turnably mounted on shaft 27a of double pulley 27.

Optionally, legs 31 may be fixed to rods 72, and legs 32 may be pivotally connected by intermediate shaft 30 to legs 31.

If the legs 32 and 31 are fixed to each other to provide angular frames, said angular frames may be turned around the axis of the intermediate shaft 27a, either to the operating full-line or non-operating broken-line positions of Fig. 1.

If legs 32 are pivotally connected to legs 31 and legs 31 are fixed to rods 72, then, as the winding operation proceeds, the legs 32 will diverge from legs 31, but the auxiliary take-up shaft 37 will always have substantially the position of Fig. 9, relative to the cutting roll or cutting drum 71.

Each leg 31 is provided with an extension 31a which is fixed rigidly to the respective leg 31. When the legs 31 are pivoted on shaft 27a and legs 31 are fixed rigidly to legs 32, and the frames 31-32 are turned into the position of Fig. 3 and Fig. 4, in which the auxiliary take-up shaft 37 is in the non-operating position, a recessed part of each extension 31a, which serves as a stop arm, contacts with a respective cross-rod 33 which is fixed to the frame F. A counter-balance weight 34, in the form of a roller, is provided at the ends of the extensions 31a. The pulley 29 is a double pulley, which drives a belt 35, which drives a pulley 36 which is fixed to a shaft 23a, which is turnably mounted at the ends of legs 32.

This auxiliary take-up shaft 37 is used only when the machine both pinks and cuts. The main take-up shaft 37a is used alone, when the machine cuts without pinking. The main take-up shaft 37a is rotated by the driven shaft 23 and the auxiliary take-up shaft 37a is rotated by shaft 23a.

As shown in Fig. 5, the main take-up shaft 37a is axially aligned with its drive shaft 23. Said main take-up shaft 37a is provided with the usual outer cylindrical mandrel or take-up tube 38, which is made of paper or cardboard or the like or other material which can be readily cut. A similar take-up tube or mandrel 38 is provided on the auxiliary take-up shaft 37.

Fig. 5 shows that one end of the drive shaft 23 ends at the line 39.

An inner collar 40 is fixed to the drive shaft 23. This collar 40 has an enlarged head, as illustrated in broken lines in Fig. 5. This head of collar 40 has a slot or recess 42 in which an extension 37b of the main take-up shaft 37a can be located with a close fit. When extension 37b is thus located, main take-up shaft 37a is rotated in unison with shaft 23.

An outer control collar 41 is turnable upon the inner collar 40. The turnable outer control collar 41 has an axial recess or slot 42a and a circumferential slot 43. The pin 44 is fixed to the inner collar 40. When the outer control collar 41 is turned to the latching position shown in Fig. 6, the pin 44 of the inner collar 40 is located at one end of the circumferential slot 43 of the outer control collar 41. When the outer control collar 41 is in the latching position of Fig. 6, the shaft extension 37b cannot be raised from the slot 42 of the inner collar 40. When the outer control collar 41 is in the release position of Fig. 7, the extension 37b registers with the axial recess or slot 42a of the outer control collar 41, so that the shaft extension 37b can be raised from the slot 42 of the inner collar 40. As shown at the left of Fig. 5, a reduced end of the main take-up shaft 37a is mounted in an open bearing of frame F by means of an anti-friction bearing 45, which can be lifted from said open bearing.

An end-collar 46 is mounted releasably upon an externally threaded end-extension 37c of the shaft 37a, in order to keep the main take-up shaft 37a assembled with its anti-friction bearing 45.

As shown in Fig. 2, a removable bar or plate 47 is detachably secured to the open bearing of the frame F. When this removable bar or plate 47 is removed from the open bearing of frame F and the control collar 41 is in the release position of Fig. 7, the entire main take-up shaft 37a can be lifted out of the frame of the machine.

The auxiliary take-up shaft 37 is similarly coupled to and turnable by shaft 23a, and said auxiliary shaft 37 is similarly detachable from the frames 31-32, so that no additional disclosure of this feature is required. Each shaft 37 and 37a is positively and mechanically driven, without depending on a frictional drive by the web of material.

Referring to Figs. 9 and 10, the web of material M which is to be slit or cut, is taken from a magazine roll R, which is wound spirally upon a mandrel or tube 48 which is mounted on a magazine shaft 49. This magazine shaft 49 is located in open bearings of the frame F, suitable anti-friction rolls 50 being provided. The magazine shaft 49 can thus be raised from its open bearings.

The magazine shaft 49 is also axially adjustable in its open bearings in the frame F. As shown in Fig. 2, magazine shaft 49 is provided intermediate its ends with a grooved collar 51 which is fixed to said magazine shaft 49. A lever 52 extends through the groove of said collar 51. This lever 52 is pivoted at 53 to the frame F. After the axial position of the magazine shaft 49 has been adjusted by means of lever 52, an extension of said lever 52 is adjustably clamped in a slot 54 of the frame F. The purpose of this axial adjustment is to properly align the edges of the material M which is taken off the roll R on the magazine shaft 49, relative to the non-pinking cutters or pinking cutters. It is univer-

sal practice to retard the rotation of shaft 49, in order to maintain the web or material M taut.

If the machine is used for cutting without pinking, the non-pinking cutting wheels 55 are used. Each cutting wheel 55 is turnably mounted in a respective cutter-holder 56. As shown in Fig. 10, a series of heads 57 are provided. Each head 57 has a slot in which a respective cutter-holder 56 is turnably mounted by means of a pivot pin 58. The heads 57 have rectangular recesses at their bottom ends, whereby said heads 57 are fitted on a rectangular holding bar 59. Said holding bar 59 is fixed to arms 72, which are later described. The heads 57 are releasably fixed to said holding bar 59 by means of clamping screws 60. A plurality of blade springs 61 of different respective lengths are fixed to the top of each head 57 by means of a respective fastening member 62. The pressure of each set of blade springs 61 is regulated by means of a respective nut 64 which is vertically movable on a screw 63 whose lower end is fixed to the respective head 57. The longest blade spring 61 of each set abuts a respective adjustable screw 65 which extends turnably into a tapped recess of the respective cutter-holder 56. Each adjustment screw 65 may be provided with a respective lock nut for holding the respective screw 65 in adjusted position.

Similar heads and associated parts are used for holding the cutting and pinking wheels.

Fig. 11 shows a cutting and pinking wheel 55a which has a series of zig-zag cutting edges, so that it cuts the material and also pinks the cut edges of the strips. Each cutting and pinking wheel 55a is mounted in a respective holder 56a, which is associated with a respective head 57, exactly as shown in Fig. 10.

When the material M is taken off the magazine roll 48, it is led in the direction of the arrow 67, around a fixed guide 68, which is fixed to frame F, then in the direction of the arrow 69, and then around a fixed guide 33 which is fixed to frame F, then towards and around part of a turnable cutting drum 71 which has suitable bearings 71a on a cross-bar which is connected to respective arms 72. This drum 71 is an idler drum which is rotated by the strip material which is moved in contact with said drum and also by the rolls of material on one or both shafts 27 and 37a. Each arm 72 has a hand-hold 73 and each arm 72 is pivoted on the shaft 27a of pulley 27. The cutting drum 71 is turned counterclockwise, as viewed in Fig. 9, by the web of material M, and also by the frictional contact with the rolls of material on shafts 37 and 37a, while maintaining pressure between the rolls of material and cutting drum 71. Said web of material M, after being slit without pinking by the cutter-knives 55, is then led in the direction of the arrow 74, and the strips are wound in respective spiral rolls of material upon the mandrel or tube 38 of the main take-up shaft 37a, which is driven clockwise as viewed in Fig. 9.

When the cutting and pinking wheels 55a are used, alternate strips are respectively wound in spiral rolls upon the respective take-up shafts 37a and 37, in order to prevent interleaving or interlocking of their adjacent pinked edges.

Referring to Fig. 9, this shows axially separated strip rolls of cut and pinked strips A, B, C, D, E and F, which have been wound up on the main take-up shaft 37a. These strip rolls are separated axially from each other. The axial distance between adjacent strip rolls is equal to

the width of one of these strip rolls. There are five spaces between the six strip rolls A-F on shaft 37a, and the five strips illustrated on auxiliary take-up shaft 37 in Fig. 9 correspond to said five spaces.

As shown in Fig. 10, when the non-pinking cutter wheels 55 are used, only the main take-up shaft 37a is used, in which case the auxiliary take-up shaft 37 and its drive shaft 23a are held in the non-operating position shown in Fig. 3.

When it is desired to thread the material M through the machine for starting the machine, or when it is desired to substitute cutting and pinking knives 55a for non-pinking cutting knives 55 or vice-versa, the arms 72 are temporarily turned to the broken-line position illustrated in Fig. 1. In this position, said arms 72 are held by the stop cross-rod 33. The arms 72 are also provided at respective corresponding ends with a counterweight roller 72a, whose shaft is adjustably fixed in the respective longitudinal slots 72b, in order to adjust the counterbalancing force of said roller 72a.

In many cases, it is desirable to inter-wind the web material M in the magazine roll R with a spiral web of paper or other separating material 80, so that adjacent windings of roll R are separated by intermediate windings of separating material 80. This separating material 80 is wound upon a hollow take-up mandrel 95. The tapered ends of heads of respective turnable shafts 81a are located in the end-parts of the hollow take-up mandrel 95. These shafts 81a are alined in respective bearings of frame F. One of these shafts 81a is provided with a driving pulley 81, which is mounted on a bearing of frame F and which is connected by belt 82 to one groove of a double pulley 83, which is fixed to a shaft 83a which is turnable in a bearing of frame F. Said pulley 83 is rotated by belt 26 which is actuated by pulley 24. Said pulley 81 is loose on the respective shaft 81a, and said pulley 81 rotates a disc 84, which is fixed to respective shaft 81a, by a friction clutch 90. Said disc 84 rotates in unison with its respective shaft 81a and said disc 84 is axially slidable on its respective shaft 81a. Said respective shaft 81a has a threaded end 87, on which a collar 86 is screwed. A compression spring 85 keeps disc 84 pressed against the corresponding end of friction clutch 90.

I have described a preferred embodiment of my invention, but numerous changes and omissions and additions can be made without departing from its scope. The invention also includes numerous sub-combinations of the machine described herein.

I claim:

1. A machine for slitting a longitudinally moving web of material into longitudinal strips, said machine having a machine frame, said machine comprising a rotatable main take-up shaft which is rotatably mounted in said machine frame to rotate about a fixed axis to wind said strips spirally in respective main strip-rolls, a rotatable idler cutting drum which is located anterior said main take-up shaft, said web being guided to contact with said cutting drum in a slitting zone which is anterior said main take-up shaft, said idler drum being rotatably connected to a drum-mount which is connected movably to said machine frame, said idler drum being biased towards said main take-up shaft to be pressed against said main strip-rolls, slitting devices located in said slitting zone and biased

towards said idler cutting drum to slit said fabric in said slitting zone, said strips being guided to contact with said idler cutting drum between said slitting zone and said main strip-rolls, an auxiliary and rotatable take-up shaft which is rotatably connected to a shaft-mount which is connected movably to said machine frame, said auxiliary take-up shaft being operative to wind some of said strips spirally thereon in respective auxiliary strip-rolls, said auxiliary shaft being biased towards said idler drum to contact said idler drum and to press said auxiliary strip-rolls frictionally against said idler drum, and means for rotating said take-up shafts simultaneously, said main and auxiliary strip-rolls being the operating means for rotating said idler drum frictionally.

2. A machine according to claim 1 in which said slitting devices are connected to said drum-mount, said slitting devices being biased relative to said drum-mount towards said idler cutting drum.

3. A machine according to claim 1 in which said drum-mount is connected by a pivot to said machine frame, said slitting devices are also connected to said drum mount, said slitting devices are biased relative to said drum-mount towards said idler cutting drum, and said idler cutting drum is located above and is biased by gravity towards said main take-up shaft when said idler cutting drum is in operating position to contact with said main strip-rolls.

4. A machine according to claim 1 in which said drum-mount is connected by a pivot to said machine frame, said slitting devices are also connected to said drum mount, said slitting devices are biased relative to said drum-mount towards said idler cutting drum, and said idler cutting drum is located above and is biased by gravity towards said main take-up shaft when said idler cutting drum is in operating position to contact with said main strip-rolls, said shaft-mount being connected by a pivot to said machine frame, said pivot having a pivot axis, said auxiliary take-up shaft being located above said main take-up shaft and being biased by gravity towards said idler cutting drum when said auxiliary take-up shaft is in operating position with its auxiliary strip-rolls in frictional driving contact with said idler cutting drum.

5. A machine according to claim 1 in which said shaft-mount is an angular frame, one end of said angular frame is connected to said machine frame, said auxiliary take-up shaft is mounted at the other end of said angular frame, said main take-up shaft is connected to drive means which include a main pulley which is rotatably mounted on said machine frame and which is rotatable about a fixed axis, an intermediate pulley which is rotatable about said pivot axis, a belt drive which connects said main pulley to said intermediate pulley, another intermediate pulley which is rotatably connected to said angular frame at the angle thereof, an additional belt drive which connects said first-mentioned intermediate pulley to said second-mentioned other intermediate pulley, said auxiliary take-up shaft having drive means on said shaft-mount which include an auxiliary pulley, and an additional belt drive which connects said second-mentioned other intermediate pulley to said auxiliary pulley.

6. A machine according to claim 1 in which said drum mount and said shaft-mount are turn-

ably connected about the same axis to said machine frame.

7. A machine for slitting a longitudinally moving web of material into longitudinal strips, said machine having a machine frame, said machine comprising a rotatable take-up shaft which is rotatably mounted in said machine frame to rotate about a fixed axis to wind said strips spirally in respective strip rolls, a rotatable cylindrical idler cutting drum which is located anterior and above said take-up shaft, said web being guided to contact with said cylindrical idler cutting drum in a slitting zone which is anterior and above said take-up shaft, said cylindrical idler drum being rotatably connected to a drum-mount which is connected movably to said machine frame, said idler drum being biased towards said take-up shaft to be pressed against strip rolls on said take-up shaft, said cylindrical idler drum being rotated only by the fric-

10

tion drive of said strip rolls, rotatable slitting discs located in said slitting zone and biased to be pressed against said cylindrical idler cutting drum to slit said fabric in said slitting zone, said strips being guided to contact with said cylindrical idler cutting drum between said slitting zone and said strip rolls, and means for rotating said take-up shaft.

DAVID N. JUDELSON.
